UNITED STATES PATENT OFFICE.

FREDERICK OTT, OF CONSHOHOCKEN, PENNSYLVANIA.

LOOSE REED-MOTION FOR LOOMS.

1,107,546.

Specification of Letters Patent. Patented Aug. 18, 1914.

Application filed September 29, 1913. Serial No. 792,307.

To all whom it may concern:

Be it known that I, FREDERICK OTT, residing at Conshohocken, in the county of Montgomery and State of Pennsylvania, have invented certain new and useful Improvements in Loose Reed-Motions for Looms, whereof the following is a specification, reference being had to the accompanying drawings.

10 An object of the invention is to provide a reed having a fixed set of blades, a movable set of blades alternating with and crossing the fixed blades, means tending to throw the movable set of blades rearwardly within 15 the spaces between fixed blades, and other means operatively engaging the movable set of blades and actuated by a fixed abutment located in the forward path thereof, so that in the forward or beating motion of the lay 20 the two sets of blades will operate together at their points of crossing as one set to beat up the weft threads, and in the backward or reverse movement of the lay the movable set of blades will be moved rearwardly between 25 the fixed blades. This object I accomplish by the mechanism shown in the accompanying drawings, in which—

Figure I, shows the parts in the position which they assume when the lay is retracted 30 and the warp threads separated by the harness, not shown, for the passage of the shuttle, not shown. Fig. II, shows the position of the reed members as they appear in the forward or "beating up" position of the lay.

35 1, designates the lay mounted on the lay-swords 2, in any approved manner. The swords 2, are actuated by the usual connecting rod 3, toward and from the breast beam 4, in the manner common to looms. The 40 reed is formed of a series of fixed blades 5, secured in the lay at their upper and lower edges in any approved manner, and a set of connected swinging blades 6, slidably held at the upper edge in a groove formed in the 45 upper bar of the lay and extending rearwardly through the rear fixed set of blades, so that two crossing comb-like structures are formed.

The lower edge of the swinging set of 50 blades 6, is pivotally connected to a cross bar 7, carried by the upper ends of a series of levers 8, only one of which is shown. These levers 8, are mounted near their lower ends on a cross bar 9, secured to the lower 55 edge of the lay 1. The levers 8, are moved rearwardly to the position shown in Fig. I,

by the contractile springs 10, one only being shown, secured at one end to the lower side of the lay 1, and at the other to the lower arms 11, of levers 8. This rearward movement of the levers 8, is limited by stops 15, projecting therefrom and engaging the under side of the lay 1, as shown in Fig. I.

The levers 8, are moved forwardly to the position shown in Fig. II, by means of an abutment 13, in the form of a cross bar secured to the loom frame 14, below and in rear of the breast beam 4. It will be seen, therefore, that as the lay 1, moves rearwardly, the arms 11, will be moved away 70 from the abutment 13, and the springs 10, will be free to act, and will move the levers 8, and the movable set of reed blades 6, rearwardly, so that a combing action is established between the two sets of reeds and 75 the warp threads 17, which are now separated for the passage of the shuttle. As the lay 1, is moved forwardly toward the breast beam, the arms 11, will engage with the abutment 13, and move the levers 8, forwardly, so that at the moment the reed is to beat up the weft thread 18, the two sets of 80 reed blades 5, and 6, will be in the positions shown in Fig. II. In this position the reed blades 5, and 6, cross each other at the 85 "beating up" point, as in the type of reed where two sets of stationary crossed blades are employed. The advantage of this latter type of reed is, therefore, present, as well as that of the reed having the movable and fixed set of crossing blades which render the use of all sorts of warps available.

It will be noticed that I dispense with all mechanism such as cams and the like movable devices for actuating the movable 95 blades 6, in the forward direction, since the arms 11, and abutment 13, obviate the necessity thereof.

Having thus described my invention, I claim:

1. A loose reed comprising a fixed set of blades, a movable set of blades loosely pivoted in advance of the fixed set and extending through the said fixed set at an angle thereto, a spring retracting the movable set, 105 and an actuating device engaging the free edge of the movable set to move it forwardly and bring its blades to the crossed beating up position with respect to the fixed blades.

2. A loose reed motion comprising a fixed set of blades, a movable set of spring-retracted blades extending through the fixed

set at an angle thereto, an actuating device connected to the free edge of the movable set of blades, and a fixed abutment in the forward path of the said actuating device, 5 whereby the two sets of reeds are brought into proper beating-up relation.

3. The combination in a loom, with the lay, of a set of fixed reed blades on the lay, an intermediate movable set of reed blades 10 loosely pivoted to the lay and extending downwardly and rearwardly through the fixed set, a lever pivoted between its ends to the lay and to the upper end of which the loose reed section is pivoted, a spring throwing the upper end of the lever rearwardly, and a fixed abutment in the forward path 15 of a portion of said lever to throw the loose reed section into beating-up position.

4. The combination in a loom, with the lay, the breast beam and an abutment between the beam and lay, of a reed carried

by the lay and formed of a fixed set of blades, a loose set of blades pivoted at their upper ends in advance of the fixed set and extending rearwardly between the fixed set, 25 a lever pivoted between its ends to the lower side of the lay and pivotally connected at its upper end to the lower free edge of the movable set, a stop extending from the lever to engage the lower edge of the lay, and a 30 spring throwing the upper end of the lever forwardly, the lower end of the lever being adapted to engage said abutment as the lay moves toward the breast beam.

In testimony whereof, I have hereunto 35 signed my name at Philadelphia, Pennsylvania, this twenty-sixth day of September, 1913.

FREDERICK OTT.
